INVENTOR:

Claudius Dornier.

UNITED STATES PATENT OFFICE.

CLAUDIUS DORNIER, OF FRIEDRICHSHAFEN, GERMANY, ASSIGNOR TO THE FIRM:
LUFTSCHIFFBAU ZEPPELIN GESELLSCHAFT MIT BESCHRANKTER HAFTUNG, OF
FRIEDRICHSHAFEN, GERMANY.

MATERIAL OF CONSTRUCTION FOR AIRCRAFT.

Application filed June 28, 1920, Serial No. 392,557, and in Germany August 21, 1918.

(GRANTED UNDER THE PROVISIONS OF THE ACT OF MARCH 3, 1921, 41 STAT. L., 1313.)

Application has also been filed in Germany August 21, 1918.

My invention refers to a novel material especially suitable for air craft on account 5 of its light weight combined with great strength.

Porous metals for the purposes of construction have been made before now, but in these the porosity itself was the main 10 thing, e. g. in accumulator plates and filter bodies. In contradistinction thereto the invention intends producing a porous material possessing the advantage of a considerably reduced weight attained by the 15 porosity.

Such a porosity can be utilized quite especially in sections, plates and similar structural parts without any danger in spite of the great strength needed, as the small 20 forces acting upon them require, such small dimensions in width, that ordinary metal cannot be used at all for practical reasons, e. g. in consideration of the knife-like edges and the injuries caused by them.

Especially the use of light metals or high class steel shows that the thickness of the sheets cannot be reduced to the limit allowing a full utilization of the resistance of the material. The present invention remedies 30 this by supplanting the solid material by the porous one, which permits using plates of considerably greater thickness due to the highly reduced weight per unit of volume.

The porosity can be obtained by chemical 35 or mechanical means or by a combination of the two.

I may for instance proceed, as described in German patent specification 257490, by heating an alloy to a temperature above the 40 melting point of more readily melting constituents of the alloy, such as the eutectic and then removing the liquefied parts by mechanical means (blowing, pressing, centrifuging and the like) from the solid res-

idue, whereby a metallic body of a density 45 inferior to rolled sheet metal is obtained, such body presenting a great number of very fine pores. I may, however, also employ perforating or punching tools of extraordinary fineness allowing to produce closely 50 juxtaposed perforations which will reduce the weight of a plate thus treated by 25 to 50 per cent without reducing its strength by anything comparable to the reduction of strength resulting from the punching out of 55 larger holes.

In the drawings a modification of some structural part is illustrated, whose material has the properties corresponding to the invention. In the drawings— 60

Fig. 1 is a cross-section and

Fig. 2 a longitudinal section of a sectional bar of U-section.

The web *a* and both flanges *b* of the bar show fine-grained sieve-like perforations. 65 Unperforated are only the transitions *d* from web to flanges and the free ends *e* of the latter. It is supposed that the U-bar is to be fastened to other structural parts by rivets. In Fig. 2 three rivet holes *f* are 70 shown. The outlines of the rivet heads are equally shown. As may be gleaned from the drawing, the fine-grained perforation is no hindrance to solid riveting. For 75 clearness sake the pores and their mutual distances as well as the rivet holes and the thickness of the plate have been shown larger than corresponds to actual conditions.

I claim:

1. A structural member for aircraft construction comprising portions made of porous sheet metal.
2. A structural member for aircraft construction comprising portions made of porous light sheet metal.

In testimony whereof I affix my signature.

CLAUDIUS DORNIER.
